(57) **CLAIM**

We claim the ornamental design for a cell phone stand, as shown and described.

DESCRIPTION

FIG. 1 is a top and front perspective view of a cell phone stand showing our design;

FIG. 2 is a front elevation view thereof;

FIG. 3 is a right side elevation view thereof;

FIG. 4 is a left side elevation view thereof;

FIG. 5 is a rear elevation view thereof; and,

FIG. 6 is a top plan view thereof.

The broken lines depict portions of the cell phone stand in which the design is embodied that form no part of the claimed, design. Additionally, the bottom plan view of the cell phone stand is hereby disclaimed and forms no part of the claimed design.

1 Claim, 6 Drawing Sheets
